UNITED STATES PATENT OFFICE.

PATRICK J. SULLIVAN, OF SAN FRANCISCO, CALIFORNIA.

WALL-SEAT.

1,183,326.

Specification of Letters Patent.

Patented May 16, 1916.

Application filed March 17, 1915. Serial No. 15,147.

To all whom it may concern:

Be it known that I, PATRICK J. SULLIVAN, a citizen of the United States, residing in the city and county of San Francisco and 5 State of California, have invented certain new and useful Improvements in Wall-Seats, of which the following is a specification.

The present invention relates to improvements in disappearing seats, which are concealed from view, and are in a position out 10 of the way when not in use.

The invention has for its principal objects to provide a seat adapted to be built 15 into the wall of a building and of a width to fit between the studding, without removing or cutting the same; to provide a structure which is capable of installation within the partition wall of a building by simply 20 removing a portion of the lath and plaster between the studding; to provide a structure wherein the seat when in a position to be occupied is provided with a suitable back or rest formed by the door which closes the 25 opening in which the seat is adapted to be concealed when not in use.

My invention is adapted for use particularly in alcoves where the space is limited 30 and where it is desired to install a telephone; in bath rooms where the space is limited and where a chair of the usual type would require too great a space when not occupied, and, in fact, in any place where it is desirable to have a seat of a type which 35 is capable, when not in use, of being easily concealed or positioned in an out of the way place.

With the above mentioned and other objects in view, the invention consists in the 40 novel construction and combination of parts hereinafter described, illustrated in the accompanying drawings and pointed out in the claims hereto appended; it being understood that various changes in the 45 form, proportion, size and minor details of construction within the scope of the appended claims may be resorted to without departing from the spirit or sacrificing any of the advantages of the invention.

To more fully comprehend the invention, 50 reference is directed to the accompanying drawings, wherein—

Figure 1 is a view in front elevation of 5 an embodiment of my invention in position between two pieces of studding and with the facing molding and door removed, disclosing the seat in folded position. Fig. 2

is a view in elevation with the facing molding and door in position. Fig. 3 is a view in vertical section of the device disclosing 60 the seat in folded position in full lines and in extended position in dotted lines.

Referring more particularly to the drawings wherein like characters of reference designate corresponding parts throughout 65 the several views, the numerals 1 indicate suitable spaced uprights, connected at the top and bottom of their front edge by the transverse members 2 and 3, which are seated in the front edges of the uprights. 70

The ends of the members 2 and 3 project beyond the uprights 1 for a slight distance, and the portion of the lower member 3 between the uprights projects a slight distance beyond the front edge of the uprights, as 75 in the drawings. A top member 4 extends between the inner surface of the uprights 1, and suitable strips 5 extend longitudinally of the inner surface of the uprights 80 a slight distance from the rear edge thereof, and to said strips are secured the members 6 forming the back. A transverse member 7 is set in the rear edge of the uprights and the lower edge thereof is in a plane slightly 85 above the upper edge of the front lower member 3 and the two provide a support for the seat when the same is in its lowered position, as in dotted lines Fig. 3.

The uprights, top, bottom and back members provide a compartment or chamber 7', 90 for the reception of the seat when the same is in its folded position.

A seat 8 is pivotally mounted between the uprights 1, and the same is carried by suitable pivot pins 9, one of which extends 95 through each upright. The seat when in its extended position will contact at its rear edge with the underside of the rear transverse member 7 and will rest on the upper edge of the forward lower member 3 and 100 will be thus supported at two points spaced from each other and will be adapted to lie in a horizontal position.

When in position in the wall, the structure forming the compartment or chamber, 105 is adapted to be inserted at the proper height between two pieces of studding 10, and the ends 11 of the members 2 and 3 are adapted to be secured to the studding preferably by being nailed.

I have provided a structure which is capable of being positioned between the studding of a building wall where the studding is spaced with standard centers, either when

the building is under course of construction or by removing a section of the lath and plaster, if it is desired to install one in a completed structure.

5 The side and top casing members 13 and 14 which are secured together by suitable dowels 15 are positioned over the uprights 1 and the top transverse member 2, and are maintained in position in any suitable manner. The casing members provide a finish for the front of the structure and conceal the rough edges of the lath and plaster and the material adjacent thereto.

The portion of the lower member 3 which 15 projects outwardly beyond the front edges of the uprights, is of a length and thickness sufficient to extend across the space between the lower ends of the side casing members 13 and completely fill the space 20 between the lower ends thereof.

A door 16 is hinged at its upper end to the top casing member 14, and the same is adapted to close the compartment within which the seat is adapted to be folded, and 25 the lower edge of said door is adapted, when the seat is in its extended position, to rest on a transverse strip 17 carried by the upper surface of the seat and provide an inclined back-rest.

30 My improved seat when it is desirable to use the same, may be readily pivoted into a horizontal position with the door providing a back rest therefor, and when it is desirable to conceal the seat, when the same is 35 not in use, it is capable of being easily enclosed in the compartment with the door forming a compartment closure.

When the cover 16 is in its lowered position, as in Fig. 2, and in full lines Fig. 3, a 40 space 18 is provided between the lower edge of the cover and the upper surface of the lower transverse member 3 and through said space access may be had to the finger recess 19 formed on the inner surface of the cover.

45 Having thus described my invention what I claim is—

1. In combination with the wall supports of a building, a seat structure for positioning between adjacent members of the same, 50 and comprising spaced uprights, top and bottom members connecting said uprights and for securing the said wall supports, a back wall secured to said uprights and providing with the uprights and said top and bottom members a chamber, a seat pivotally mounted between said uprights and capable of pivotal movement downwardly to a horizontal position, means for limiting the downward movement of said seat, and a 55 cover for said chamber hinged at its upper end and providing a back for said seat when the same is in its horizontal position.

60 2. In combination with the wall supports

of a building, a seat structure for positioning between adjacent members of the same 65 and comprising spaced uprights, means for securing the same to said wall supports, a seat pivotally mounted between said uprights and capable of pivotal movement downwardly to a horizontal position, means for limiting the downward movement of said seat, and a hinged cover for concealing said seat when the same is in a folded position between said uprights and providing an inclined back for said seat when the 75 same is in a substantially horizontal position.

3. A seat cabinet comprising spaced uprights, top and bottom members connecting the same, a back member, said uprights, 80 top, bottom and back member forming a cabinet, a seat pivotally mounted between said uprights and capable of reception within said cabinet, said seat also capable of pivotal movement downwardly to a substantially horizontal position, means for limiting the downward movement of said seat, and a cover for said cabinet, said cover co-operating with said seat when the same is in its substantially horizontal position for 90 providing an inclined back therefor.

4. In combination with the wall supports of a building, a seat structure for positioning below adjacent members thereof, comprising spaced uprights for securing to said 95 wall supports, a seat pivotally mounted between said uprights and capable of pivotal movement to swing between the same, said seat also capable of pivotal movement downwardly to a substantially horizontal position, 100 means for limiting the downward movement of said seat, and a door for concealing said seat when swung between said uprights, said door when said seat is in a substantially horizontal position providing an inclined back therefor.

5. A cabinet seat comprising spaced uprights, a seat pivotally mounted between said uprights and capable of pivotal movement to swing between the same, and of 110 pivotal movement downwardly to a substantially horizontal position, means for limiting the downward movement of said seat, and a hinged door for concealing said seat when swung between said uprights, said 115 door when said seat is in a substantially horizontal position providing an inclined back therefor.

In testimony whereof I have signed my name to this specification in the presence 120 of two subscribing witnesses.

PATRICK J. SULLIVAN.
